Ohio, a corporation of Ohio

Application December 6, 1937, Serial No. 73,396

Term of patent 7 years

To all whom it may concern:

Be it known that I, Francis F. Braun, a citizen of the United States, residing in Cincinnati, in the county of Hamilton and State of Ohio, have invented a new, original, and ornamental Design for a Paper File or Similar Article, of which the following is a specification, reference being had to the accompanying drawing, forming part thereof.

In the drawing:—

Figure 1 is a plan view of a paper file showing my new design.

Figure 2 is a front elevation thereof.

Figure 3 is a side elevation thereof.

The dominant features of the design comprise the streamlined appearance of the base plate, said plate being thicker at the top than at the bottom giving the appearance of a semi-teardrop, together with the sloping contour of the top of the base and the raised portions forming the bases for the file arches.

I claim:

The ornamental design for a paper file or similar article, as shown and described.

FRANCIS F. BRAUN.
